UNITED STATES PATENT OFFICE.

HENRY B. BURDICK, OF MIDDLETON, OKLAHOMA TERRITORY.

AUTOMOBILE PLOW.

SPECIFICATION forming part of Letters Patent No. 766,590, dated August 2, 1904.

Application filed April 24, 1903. Serial No. 154,149. (No model.)

To all whom it may concern:

Be it known that I, HENRY B. BURDICK, a citizen of the United States, and a resident of Middleton, in the county of Kay and Territory of Oklahoma, have invented a new and Improved Automobile Plow, of which the following is a full, clear, and exact description.

The purpose of my invention is to construct a simple and economic form of plow in which the motive power is carried upon the frame of the plow and is suitably connected with the bull or driving wheel and to provide means readily accessible to the operator for steering the machine, adjusting it for hillside work, and regulating the depth to which the plow shall enter the ground.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a side elevation of the machine. Fig. 2 is a plan view of the same. Fig. 3 is a front elevation. Fig. 4 is a detail view illustrating the means for adjusting the rear left-hand supporting or land wheel. Fig. 5 is a detail view illustrating the manner in which the forward end of the beam is connected with the frame of the machine. Fig. 6 is a horizontal sectional view on the line 6 6 in Fig. 1 through the bull-wheel of the machine, illustrating the manner in which it is supported and the adjusting mechanism for the wheel; and Fig. 7 is a vertical section on the line 7 7 in Fig. 2 through the forward portion of the frame, showing the manner in which the forward end of the plow-beam is raised and lowered to regulate the inclination of the plow-point in entering the ground.

A represents the frame of the machine, which consists of a main section 10 and a side extension 11. On this side extension an engine B is suitably supported, together with a boiler C or a gasolene-tank or its equivalent. At the rear of the frame A a platform 12 is preferably located, and above the said platform at the rear of the main section 10 of the

frame the driver's seat 13 is secured. A pinion 14 is located on the drive-shaft of the engine B, and this pinion 14 meshes with a gear 15, which gear is secured to a driving-shaft 16, suitably mounted upon the main section 55 10 of the frame A, as is best shown in Fig. 2. A clutch 17 is mounted to slide upon the shaft 16 and turn therewith, and a spring 18 is made to exert pressure upon the said clutch 17 in such manner as to bring the clutch in 60 locking engagement with the hub of a sprocket-wheel or pulley 19, loosely mounted on the said shaft 16, as is also shown in Fig. 2.

An axle 20 is mounted in the extension 11 of the frame and in the adjoining portion of 65 the main section 10 of the frame. The axle 20 is located near the rear end of the said frame A and at its outer end is provided with a crank-arm 20^a, and upon the projection from said crank-arm the left-hand supporting- 70 wheel or land-wheel 21 is mounted to loosely turn. A lever 22 is loosely mounted on the outer end of the straight portion of the axle 20, as is best shown in Fig. 4, which lever is provided with a thumb-latch 23, adapted for 75 engagement with a rack 24, secured to the aforesaid extension-section 11 of the frame A, and the said lever 22 is connected by a link 25 with a projection 25^a from the crank-arm of the said axle 20, the said projection being 80 adjacent to the hub of the said wheel 21, so that by the operation of the lever 22 the left-hand supporting or land wheel 21 may be raised and lowered to level the machine when employed in hillside work. 85

A bull or driving wheel D is loosely mounted upon a shaft 26, which shaft is supported at its left-hand end in a suitable bearing 26^a at the left-hand side of the main section 10 of the frame A, as is shown in Figs. 2 and 6. This bearing is so constructed that the shaft 26 has vertical movement in the bearing. The opposite end of the shaft 26 extends in a bearing 39^a in the form of a fixed link, which is at the right-hand side of the main section 10 of 95 the frame A. This bearing is more or less vertically disposed, as is the opposing bearing 26^a, and at the forward inner edge of the said bearing 39^a teeth 40^a are produced. A pinion 39^b, which is secured at the right-hand 100

end of the shaft 26, on which the bull-wheel D is loosely mounted, is adapted to engage with the said teeth 40^a for the purpose of raising and lowering the bull-wheel in order to 5 raise or lower the body of the machine, so that the plow, to be hereinafter described, may be raised a sufficient distance from the ground to pass obstructions when the machine is to be carried from one point to another or 10 so that the plow may be dropped quickly with the frame to rest upon the ground when the field to be plowed is reached. This adjustment of the bull-wheel is accomplished by securing a worm-wheel 77 on the shaft 26 and 15 causing the said worm-wheel to be engaged by a worm 78, held to turn in suitable bearings attached to the left-hand side of the main section 10 of the frame A, and this worm 78 is preferably provided with a polygonal socket, 20 in which a handle 79 may be introduced for the purpose of turning the worm and raising and lowering the said bull-wheel when required. A large sprocket-wheel 27 is likewise mounted loosely on the shaft 26, and this 25 sprocket-wheel 27, as is shown in Fig. 6, is secured to the bull-wheel D, so that the two turn together. A chain belt 27^a or its equivalent is passed over the sprocket-wheel 27 and over the smaller sprocket-wheel 19 on the drive- 30 shaft 16. The lower stretch of the belt 27^a is engaged by an idler 28, carried by an arm 29, extending downward from the frame at its right-hand side, as is shown best in Fig. 1, and a tension-roller 30 is made to engage with the 35 upper stretch of the chain, which tension-roller 30 is mounted upon a crank-arm 31, held to turn in a suitable standard 32, carried up from the right-hand side of the frame A, and at the outer or right-hand end of the said 40 crank-arm 31 a bar 33 is centrally attached. A spring 34 is secured to the upper end of the said bar and to a rod 35, which extends forwardly and is secured to the forward right-hand portion of the frame A, the said rod 35 being provided with a turnbuckle 36, so that 45 the spring 34 may be placed under more or less tension. Further, a second spring 37 is secured to the lower end of the bar 33, and this latter spring extends rearwardly and is 50 attached firmly at its rear end to the rear portion of the frame A at its right-hand side, as is shown in both Figs. 1 and 2.

The clutch 17 is carried out of clutch engagement with the pulley or sprocket-wheel 55 19 on the drive-shaft 16 through the medium of a lever 38, which is suitably mounted on a transverse support 38^a, located on the main section 10 of the frame, and the rear portion of this lever 38 is made to engage with a trans- 60 verse rack 39, likewise carried by the main section 10 of the main frame A. The handle end of the shifting-lever 38 is within convenient reach from the driver's seat 13.

The forward portion of the frame A is sup- 65 ported by a carriage E, which carriage, as is

best shown in Figs. 3 and 7, consists of a central yoke-section 40, in which a vertically-disposed king-bolt or pivot-pin 41 is located. This yoke-section 40 is provided at each side of its upper portion with horizontal brackets 42 and at the lower portion of its left-hand side with a larger bracket 43, in which bracket and in the left-hand leg of the yoke 40 an axle 44 is suitably mounted, having a crank-arm 45 at its outer end, and on a spindle carried 70 from the said crank-arm the left-hand forward supporting or land wheel 46 is mounted to turn. This axle 44 may be turned so as to raise or lower the said left-hand supporting-wheel 46 through the medium of a lever 47, 80 which is secured to the axle 45 and is provided with a thumb-latch 48, engaging a rack 48^a, carried by the said bracket 43, as is clearly shown in Fig. 3.

An axle 49 is secured to the right-hand side 85 of the yoke 40 of the carriage E at the lower portion of said yoke, and this axle is supported by a bracket 50, attached to the right-hand upper bracket 42, as is also shown in Fig. 3, and on the outer end of the axle 49 90 the right-hand forward supporting-wheel 52 of the frame is loosely mounted. This carriage is attached to the forward portion of the main section 10 of the frame A by an angle bracket or arm 53, as is shown in Fig. 1. 95 At the rear of this angle arm or bracket 53 a transverse box-frame 54 is secured upon the main frame, and preferably a plate 55 is carried from the angle-arm 53 over to the said box-frame 54.

A vertical shaft 56 is mounted to turn in the box-frame, and within the box-frame on the said shaft 56 a drum 57 is secured in any approved manner. At the upper end of the shaft 56 above the box-frame 54 a bevel-gear 58 is attached. A chain 59 is wound around the drum 57, having its ends attached to posts 60, which extend up from the upper brackets 42 at the sides of the yoke-section 40 of the carriage E.

The forward end of a steering-shaft 62 is journaled in a suitable bearing 61, supported by the plate 55, as is shown in Fig. 1, and on this steering-shaft 62 a bevel-pinion 63 is secured, meshing with the teeth of the bevel-gear 58, and the said steering-shaft 62 is carried rearward within convenient reach of the driver's seat and terminates at its rear end in a crank-handle 63^a, so that by turning the said handle 63^a the direction of travel of the machine may be speedily changed as desired.

A plow-beam F is located beneath the main section 10 of the frame A, which beam has the usual forward and downward curvature and carries at its rear end a share 64, the landside of which is practically in alignment with the landside of the bull or driving wheel D, as is shown in Fig. 2. The forward end of the plow-beam F is provided with an eye 65, mounted to slide upon the king-bolt 41. 130

Braces 66 are pivoted upon studs 67 at each side of the rear portion of the beam F, and said braces have their forward ends pivoted to the side members of the section 10 of the frame A, as is shown in Figs. 1 and 2 and as is illustrated in Fig. 5. Where the eye 65 connects with the beam F an upwardly-extending member 65^a is located, whereby to adjust the inclination of the point of the plow-share by raising and lowering the forward end of the plow-beam F. This adjustment of the forward end of the plow-beam is accomplished, as is shown especially in Figs. 1 and 7, by connecting a vertical rod 80 with the said upwardly-extending member 65^a, which rod at its opposite end is pivotally attached to one limb, 81^a, of an elbow-lever 81, journaled in suitable bearings 82 on the forward upper plate 55 of the main frame, the other limb, 81^b, of the said elbow-lever 81 being pivotally connected with a link 83, which is carried to the rear of the machine out of the way of the other mechanism and is attached at the rear to a hand-lever 84, provided with a suitable hand-latch for engagement with a rack 85, the hand-lever 84 being within convenient reach of the operator when occupying the seat 13. Thus it will be observed that at the will of the operator the point of the plowshare may be raised or lowered or may be given any inclination the character of the ground may demand.

The plow and its beam may be bodily raised and lowered by the following mechanism: A link 68 is pivoted upon one lug or stud 67 and upon the crank-arm 69, extending forwardly and outwardly from a shaft 70, journaled in suitable bearings 71, carried by the main section 10 of the main frame A, and this shaft is provided at its outer right-hand end with an upwardly and rearwardly inclined crank-arm 72, connected by a link 73 with a lever 74, fulcrumed at the right-hand rear portion of the frame A within easy reach of the driver's seat. This lifting-lever for the plow-beam has the usual thumb-latch 75, adapted for engagement with a rack 76 on the frame A.

It will be understood that in the arrangement of the several parts the bull-wheel D must be so placed that it will keep in the furrow made by the plow.

Having thus described my invention, I claim as new and desire to secure by Letters Patent—

1. A frame, a driving and a supporting wheel at opposite sides of the rear portion of the frame, the supporting-wheel being adjustable, a two-wheel-supported carriage pivotally connected at the forward end of the frame, means for raising and lowering one of the wheels of the carriage, a steering mechanism for the carriage, a motor supported by the frame, a connection between the motor and the driving-wheel, a plow-beam having its forward end adjustably supported by the car-

riage, and a lifting mechanism for the plow-beam located on the said frame, as set forth. 65

2. A frame, supporting - wheels for the frame one of which is a driver, and vertically movable, a motor carried by the frame and connected with the driving-wheel, and a mechanism for raising and lowering the driving-wheel independently of the supporting-wheels, substantially as described. 70

3. A frame, supporting - wheels for the frame, one of which is a driver and vertically movable, means for raising and lowering the driving-wheel, a motor carried by the frame, a connection between the motor and the driving-wheel, a mechanism for bodily raising and lowering the plow-beam, and an independent 80 raising and lowering mechanism connected with the forward end of the plow-beam, and adapted to regulate the angularity of the plow-point with reference to the ground, substantially as described. 85

4. A frame, a driving and a supporting wheel at opposite sides of the rear portion of the frame, devices for raising and lowering said wheels independently of one another, a carriage pivotally attached to the forward portion of the rear section of the frame, wheels for the carriage, a device for raising and lowering one of the said wheels of the carriage, a plow-beam pivotally connected with the carriage, a lifting device for the plow-beam, a motor, and a driving connection between the motor and the driving-wheel, as described. 90

5. A wheel-supported frame comprising a rear main section and a forwardly-pivoted section, a steering mechanism for the forward section, a motor, a belt connection between the motor and one of the supporting - wheels, a tension device for the belt, a plow-beam having a pivotal and vertically-adjustable connection at its forward end with the forward section of the frame, a lifting mechanism carried by the main section of the frame, and a connection between such mechanism and the rear portion of the plow-beam, substantially as described. 100 105 110

6. A wheel-supported frame, comprising a rear main section and a forwardly-pivoted section, a steering mechanism for the forward section, a motor, a belt connection between the motor and one of the supporting - wheels, a tension device for the belt, a plow-beam having a pivotal and vertically-adjustable connection at its forward end with the forward section of the frame, a lifting mechanism carried by the main section of the frame, a connection between such mechanism and the rear portion of the plow-beam, and means for adjusting the supporting-wheels at the left-hand or land side of the machine, as set forth. 115 120

7. In a plow, a frame, a shaft having one 125 end loosely mounted in a bearing, a fixed yoke provided with teeth and through which the other end of the shaft passes, a pinion on the

shaft and meshing with the teeth of the yoke, a driving-wheel loosely mounted on the end of the shaft, and means for turning said shaft, as set forth.

5 8. In a plow, a frame, a shaft having one end loosely mounted in a bearing, a worm-wheel on the shaft adjacent to said bearing, a worm engaging the worm-wheel, means for operating the worm, a yoke provided with 10 teeth and through which the other end of the said shaft passes, a pinion on the shaft and meshing with the teeth of the yoke, and a driving-wheel loosely mounted on the end of the shaft projecting through the yoke, as set 15 forth.

9. In a plow, a frame, supporting-wheels one of which is a driver, a motor mounted on the frame, a driving-shaft geared with the motor, a sprocket-wheel on the driving-shaft, 20 a sprocket-wheel on the driving-wheel, a chain belt passing over said sprocket-wheels, a clutch on the driving-shaft, and means for operating the clutch, as set forth.

10. A plow, comprising a main frame, supporting-wheels for the main frame, of which one is a driving-wheel, a carriage to which the forward end of the frame is pivoted, a steering device for the carriage, a motor on the main frame, a driving-shaft geared with 25 the motor, gearing between the driving-shaft and the driving-wheel, and a plow having its beam pivotally connected with the frame and carriage, as set forth.

11. In a plow, a wheel-supported frame comprising a rear main section and a forward pivoted section, a plow having the forward end of its beam slidably mounted on the pivot of the forward section of the frame, means 30 for raising and lowering the said forward end of the plow-beam, links pivoted to the rear frame-section and to the plow-beam near its rear end, a shaft provided with a crank-arm at

each end, a link connecting one crank-arm with the plow-beam, an operating-lever, and a link connecting the lever with the other 45 crank-arm of the said shaft, as set forth.

12. In a plow, a frame, a driving-shaft, a sprocket-wheel on said shaft, a driving-wheel mounted in the frame and carrying a sprocket-wheel, a chain belt passing over the sprocket-wheels, a crank-arm, a tension-roller on the crank-arm and engaging the chain belt, a bar secured at its center to the crank-arm, and springs secured to the ends of the bar and to the frame, as set forth. 50

13. In a plow, a main frame, supporting-wheels for the main frame, a carriage to which the forward end of the frame is pivoted, a plow having the forward end of its beam slidably mounted on the pivot connecting the 60 frame and carriage, means for adjusting the forward end of the beam, a pivotal connection between the plow beam and frame, and means for raising and lowering the plow, as set forth. 65

14. In a plow, a main frame, supporting-wheels for the frame, one wheel being a driver and each independently adjustable, a motor on the frame, means for operating the drive-wheel from the motor, a two-wheeled carriage 70 to which the forward end of the frame is pivoted, one of the wheels of the carriage being adjustable, a steering device for the carriage, and a plow having the forward end of its beam slidably connected with the carriage and its 75 rear end pivotally connected with said frame, as set forth.

In testimony whereof I have signed my name to this specification in the presence of two subscribing witnesses.

HENRY B. BURDICK.
